5 Claims. (Cl. 28—1)

This invention relates generally to the production of bulked filamentary yarn and more particularly to improvements in a bulking apparatus which includes a jet device through which the yarn advances to a moving foraminous surface.

In the operation of such an apparatus, because of the high noise level associated with the fluid stream passing through the jet orifice, various remedies such as earplugs and acoustical enclosures have been adopted. Even with an acoustical enclosure, earplugs are still required when the enclosure is opened for threadline stringup since the jet must be turned on to assist in overcoming frictional drag on yarn contact surfaces. With the jet turned off, an effective stringup cannot be made through the normal threadline path of advance along the foraminous surface.

The most important object of this invention is to eliminate the need for operation of the fluid jet during stringup of an apparatus used for producing bulked yarns. A more particular objective is to provide a movable guide for diverting a threadline from its normal path of advance through the apparatus enclosure and a remote control for releasing it after the jet has been placed in operation. A further objective is to reduce frictional drag on the yarn during stringup of a yarn bulking position.

These objectives have been achieved with an apparatus located in an acoustical enclosure and including a driven drum having a foraminous surface around which filamentary yarn normally advances from a jet to a stationary guide and an auxiliary guide means for diverting the yarn from that surface during stringup. As components, the auxiliary guide means is comprised of a fixed support, an arm having a freely rotatable roll projecting from one of its ends, a pivot pin mounting the arm on the support for swinging movement of the roll to and from a normal position of spaced parallelism with the drum surface and an actuator pin in contact with the arm adjacent its other end for swinging the roll to a tilted, yarn-releasing position.

Other objectives and advantages will be apparent from the following specification wherein reference is made to the accompanying drawings in which:

FIGURE 1 is a front perspective view of a bulking apparatus into which the improvements of our invention have been incorporated; and

FIGS. 2, 3 are side and front elevations, respectively, of the swingable auxiliary guide shown in FIG. 1.

In the embodiment chosen for purposes of illustration, filamentary yarn 10 from a supply bobbin 12 is passed around a pair of metering rolls 14. After opening a door 16 on enclosure 18, yarn 10 is introduced through slot 20 and is passed through jet 22 over a freely rotatable roll 24, to prevent contact with the foraminous surface of a driven drum 26 during the stringup operation. In FIGS. 1, 2, that surface has been shown as a screen. Jet 22 is mounted on a pedestal which extends from a side wall 28 of enclosure 18 and normally receives air under pressure from a source connected to an inlet conduit 30.

2

While door 16 is open, operator exposure to high noise levels is avoided by first turning off the air supply. From roll 24, the yarn is routed around a stationary guide and through slot 34 to a second pair of metering rolls 36. Thus, the high frictional drag encountered by yarn 10 in its normal path of advance 38 around the foraminous surface of drum 26 is avoided by diverting it to roll 24. These stringup steps are accomplished manually with sucker gun or other available stringup aids (not shown). Following stringup, door 16 is closed, jet 22 is turned and yarn 10 is released to drum 26 by depressing a pin which tilts roll 24 downwardly.

Referring to FIGS. 2, 3, roll 24 is freely rotatable on shaft 42 which projects from one end of an arm 44 a cantilever. At a point between its ends, arm 44 is attached to the depending leg of a fixed support 46 means of a pivot pin 48 having its axis substantially perpendicular to that of drum 26. Adjacent its other end arm 44 has a flat surface 50 adapted for bearing engagement with the horizontal leg of support 46 which is fastened to top wall 52 of enclosure 18 by screws 54. At this time, roll 24 is in spaced parallelism with the surface of drum 26. Top wall 52 and support 46 are provided with aligned openings through which actuator pin 40 extends. Pin 40 contacts and rests on surface 50. The tension of yarn 10 pulls on roll 24 and thus tends to hold surface 50 in bearing engagement with support 46. When pin 40 is depressed, arm 44 is pivoted in a counterclockwise direction (FIG. 2) and roll 24 is tilted downwardly, thus releasing yarn 10 to its normal path of advance 38 between jet 22 and stationary guide 32.

Instead of a freely rotatable roll, the diverting guide could be a pin or stationary extension of arm 44. Other changes and modifications of a similar nature will occur to those skilled in the art without departure from the spirit of our invention which accordingly is intended to be limited only by the scope of the appended claims.

Having thus described the invention, what is claimed as new and desired to be secured by Letters Patent is:

40. 1. In an apparatus including a driven drum having a foraminous surface around which yarn normally advances between spaced elements, guide means for diverting the yarn from said surface during stringup, said guide means comprising: a fixed support; an arm; means mounting said arm, at a point between its ends, on said support for swinging movement about an axis substantially perpendicular to that of said drum, one of said ends being adapted for engagement with said support; a cylindrical guide projecting from said arm adjacent its other end; said guide being in substantial parallelism with the drum axis when the support is engaged by said one end of the arm; and an actuator associated with said arm for swinging said one end away from the support whereby to said guide downwardly out of parallelism with said drum axis and release the yarn to said surface.
45. 2. The apparatus of claim 1 wherein said cylindrical guide is a freely rotatable roll.
50. 3. The apparatus of claim 1 wherein said actuator is a pin extending through said support with one of its ends contacting said one end of the arm.
55. 4. In an apparatus including an enclosure defined by walls and a door and, within said enclosure, a driven drum having a foraminous surface around which yarn normally advances between a jet and a stationary guide, auxiliary guide means for diverting the yarn from said surface during stringup, said auxiliary guide means comprising: a fixed support; an arm; means mounting said arm, at a point between its ends, on said support for swinging movement about an axis substantially perpendicular to that of said drum, one of said ends being adapted for engagement with said support; a cylindrical guide projecting from said arm adjacent its other end; said guide being in substantial parallelism with the drum axis when the support is engaged by said one end of the arm; and an actuator associated with said arm for swinging said one end away from the support whereby to said guide downwardly out of parallelism with said drum axis and release the yarn to said surface.
60. 5. The apparatus of claim 4 wherein the actuator is a pin extending through said support with one of its ends contacting said one end of the arm.
65. 6. The apparatus of claim 4 wherein the actuator is a pin extending through said support with one of its ends contacting said one end of the arm.

3

stringup, said auxiliary guide means comprising: a port fixed to one of said walls, within the enclosure; an having a cylindrical guide projecting from one its ends; means mounting the arm on said support for nging movement of said cylindrical guide to and from ormal position in which it is in spaced parallelism b said surface; and an actuator pin extending through 1 one wall and contacting said arm adjacent its other whereby to swing the cylindrical guide downwardly of parallelism with said surface and release the yarn said surface.

5. The apparatus of claim 4 wherein said cylindrical guide is a freely rotatable roll.
